INVENTOR

Samuel Krause.

By Ralph Reich
ATTORNEY

UNITED STATES PATENT OFFICE.

SAMUEL KRAUSE, OF ST. LOUIS, MISSOURI.

WINDOW LOCK.

Application filed December 15, 1924. Serial No. 755,970.

To all whom it may concern:

Be it known that I, SAMUEL KRAUSE, a citizen of the United States, residing at the city of St. Louis, State of Missouri, have 5 invented a certain new and useful Improvement in Window Locks, of which the following is a specification, reference being had to the accompanying drawing, forming a part thereof.

10 This invention relates to a certain new and useful improvement in window locks and has for its chief object the provision of a lock adapted for conveniently securing the sashes of a window, both upper and lower, 15 against relative movement, the lock being simple and inexpensive in form and construction and comprising few co-operating and readily installed parts.

And with the above and other objects in 20 view, my invention resides in the novel features of form, construction, arrangement, and combination of parts hereinafter described and pointed out in the claims.

In the accompanying drawing—

25 Figure 1 is a fragmental elevational view of a window and its sashes equipped with a lock embodying my invention, the co-operating parts of the lock being in sash-locking engagement;

30 Figure 2 is a similar view with the parts of the lock in disengagement and the sashes of the window unlocked; and

35 Figure 3 is a somewhat enlarged sectional plan view with the parts of the lock in sash-locking engagement in full lines as in Figure 1, and in sash-unlocked disengagement in dotted lines as in Figure 2.

Referring now more in detail and by reference characters to the drawing, which illustrates a preferred embodiment of my 40 invention, A designates a window-frame, and B and C the upper and lower sashes, respectively, arranged for relative slidable movement in the frame A, as will be well understood.

45 Fixed at its shank 1 in one of the side-members 2 of the upper sash B to extend over the lower member 3 thereof and approximately parallel with the inner face or plane of the glass 4, is one of the lock-members D, which is preferably in the form of an angular hook having its bill 5 presented downwardly towards the upper member 6 of the lower sash C.

50 E designates the co-operating member of the lock, which is preferably in the form of

substantially L-shaped hook, as best seen in Figures 1 and 2. As there shown, lock member E comprises a base or shank 7 disposed approximately flatwise upon the upper 50 face of the upper member 6 of lower sash C, a bill 8 extending somewhat over and approximately parallel with shank 7 and having an aperture 9 for accomodating the bill 5 of hook-member D, and a piece 10 55 connecting shank 7 and bill 8, the member E being attached or secured, as by means of a screw-pin or the like 11 projected through its shank 7 and into the sash-member 6, for swivelling or swinging movement relative 60 to the window-sashes and in co-operative relation to the upper sash hook D.

It will be understood that, while I here merely show the lock-members D and E upon the right-hand side of the window-frame A, they are preferably duplicated upon the other or left-hand side of the window. It will also be understood that the lock-members D may be fixed upon the upper sash B at any selected location relatively 75

close to or removed from the lower member 3 of the sash, corresponding to the distance of relative movement, if any, desired in the lower sash C when the lock-members D and E are in engaging registration. In 80

the present instance, the lock-members D are fixed in the side-members 2 of the upper sash B, say, at a distance of five inches from the lower-member 3 of the sash, thereby permitting relative movement of the lower sash 85

90 C through a corresponding distance when the lock-members D and E are in engaging registration. Normally, as when the lock-members are in such engaging registration, the lower lock member E is swung to project at its shank 7 and bill 8 over and at approximately right angles to the upper member 6 of the lower sash. When in such 95

registration, it will now become evident that, though the lower sash C may be opened to 100 a corresponding distance of five inches, as for room-ventilating purposes, the bill 5 of the member D will engage in the aperture 9 of the bill 8 of the member E as soon as the lower sash C has been opened or ele- 105

vated through such distance and thereby securely prevent further opening movement of the lower sash. Correspondingly, with the lower sash C closed, the upper sash B may be lowered only until its carried lock-member D engages at its bill 5 in the bill 8 of the lock-member E of the lower sash 110

C, when further movement of the upper sash will be similarly securely prevented. A swinging of the lower lock-member E to project in parallelism over the upper member of the sash C, as shown in full lines in Figure 2 and as indicated by dotted lines in Figure 3, permits both sashes of the window to be opened to their full limit.

Thus, by means of my new lock, which is 10 exceedingly simple and most conveniently installed, I am enabled to either lock both sashes of the window against any relative member or to permit relative opening movement of the sashes through selected distances within the limits of their frame.

I am aware that minor changes in the form, construction, arrangement, and combination of the several parts of my new lock may be made and substituted for those here- 20 in shown and described without departing from the nature and principle of my invention.

Having thus described my invention, what I claim and desire to secure by Letters Patent is:

1. A window-lock including a hook-member adapted for rigid securing upon the side member of the upper sash to extend over and approximately parallel with the 30 lower member thereof, the bill of the hook

being presented downwardly, in combination with a co-operating substantially L-shaped hook-member including a shank, an apertured bill disposed over and approximately parallel with the shank, and a piece 35 connecting the shank and bill, the second hook-member being adapted for pivotal securing at its shank upon the upper member of the lower sash to swing into and out of engaging registration at its apertured bill 40 with the bill of the first hook-member.

2. In combination with a window-frame and its relatively slidable upper and lower sashes, of a hook-member rigidly fixed upon the side member of the upper sash to extend over and approximately parallel with the lower member thereof, the bill of the hook being presented downwardly, and a co-operating hook-member including a shank, an apertured bill disposed over and approximately parallel with the shank, and a piece 45 connecting bill and shank, the second hook-member being swivelled upon the upper member of the lower sash to swing into and out of engaging registration at its apertured bill with the bill of the first hook-member.

In testimony whereof, I have signed my name to this specification.

SAMUEL KRAUSE.
